UNITED STATES PATENT OFFICE.

JOHN B. BEAUV AIS, OF HOLYOKE, MASSACHUSETTS.

WATER-HEATING APPARATUS.

No. 904,297.

Specification of Letters Patent.

Patented Nov. 17, 1908.

Application filed August 27, 1907. Serial No. 390,318.

To all whom it may concern:

Be it known that I, JOHN B. BEAUV AIS, a citizen of the United States of America, and resident of Holyoke, in the county of Hampden and State of Massachusetts, have invented certain new and useful Improvements in Water-Heating Apparatuses, of which the following is a full, clear, and exact description.

10 This invention relates to an apparatus for heating the water in an ordinary kitchen boiler tank comprised in the plumbing arrangements of a house, or for heating the water in another receptacle as it may be practicable in some cases to do.

15 This heating apparatus is designed to operate independently of any water front heater in a stove, and to do the work of such water front heater, although it may be employed in some cases as an auxiliary thereto.

20 The principal object of the invention is to provide a water heating apparatus of the character indicated which will be available for heating considerable quantities of water 25 by the employment of a gas or other suitable burner in very much less time than has heretofore been necessary; and the apparatus has furthermore been devised with a view to producing a gas heating apparatus which, by 30 reason of the construction and organization or co-operative arrangement of the parts thereof, is comparatively simple and extremely inexpensive.

35 The invention comprises in a heating apparatus an inclosed hollow axially vertical annular metallic body, a supply pipe leading thereinto for water to be heated, a hot water delivery pipe therewith connected and leading from the inclosed annular chamber there- 40 in, and a gas burner below, and for heating the annular body.

45 The invention furthermore includes a construction of annular inclosed heater body having a multiplicity of metallic studs connected with and extended transversely from the circular walls thereof together with an arrangement of gas burner whereby the jet 50 flames thereof will impinge, or be directed against or relatively to both the annular bottom of the heater body and the studs projecting from the side walls thereof.

55 The invention furthermore consists in certain particular combinations and arrangements of parts and the constructions of cer- tain of the parts all substantially as herein-

after fully described and set forth in the claims.

In the drawings:—Figure 1 shows the improved heater in central vertical section connected for operation in conjunction with an ordinary kitchen boiler tank. Fig. 2 is a plan view of parts, on a larger scale, as seen below the plane indicated by line 2—2, Fig. 1, the same particularly showing the compound gas heating burner. Fig. 3 is a sectional view on line 3—3, Fig. 1. Line 1—1, on Fig. 3, indicates the plane on which portion of the view Fig. 1, which is in section, is taken. Fig. 4 is a plan view, and Fig. 5 is a side elevation of the water heating apparatus, the inclosing casing or shell in Fig. 5 being represented in section as taken on the line 5—5, Fig. 4.

Similar characters of reference indicate corresponding parts in all of the views.

In the drawings,—A represents the heater-body constructed as an inclosed, hollow axially vertical annular cast iron or other metallic casing provided with a multiplicity of metallic studs a extended radially, or substantially transversely, with suitable spacing one from another from the outer cylindrical surface of the body; and said body also has a similar series of inwardly projecting metallic studs a^2 connected with and radially projected from its inner wall.

B represents an ordinary house boiler tank from which the pipe b leads,—from the lower portion thereof into the annular chamber in the heater-body A, the same, as shown in Fig. 1, preferably extending downwardly within such chamber to a point near the bottom thereof.

c represents the hot water delivery pipe which leads from the top of the annularly chambered heater-body A to connection with the usual pipe c^2 connected with and extended upwardly from the top of the boiler tank and understood as having connection usually with the hot water faucets at the kitchen sink, in the bath room and at various other locations in the house.

The cast iron or other metallic heater body A has formed thereon or attached thereto near the base thereof a plurality of comparatively short outwardly extending lugs d which are vertically perforated.

The letter D generally represents the compound gas burner provided as a part of the present apparatus. This burner comprises

110

2 a main annular hollow burner body or casing *f* having its location under and in suitable proximity to the annular base of the heater body, and it has double circular series of upwardly open gas burner jets 10, 10 to give flame impingements directly against the base of the heater body *A*.

10 *f*² represents the pipe for supplying gas into the main annular burner, air in conjunction with such gas being taken into the burner by well known provisions indicated at *f*³ and requiring herein no particular description.

15 The burner *D* is supported by being suspended from the low portion of the heater body *A* through means of L-shaped members *g*^{*} as particularly represented in Figs. 1, 2 and 5 which have connections with the outer side of the main burner body *f* while their 20 vertical limbs are extended upwardly through the perforations in the aforementioned lugs *d* of the heater body and are therewith connected by nuts 13, 13, or other equivalent fastenings.

25 The L-shaped supporting members, being tubular, in communication with the chamber in the main annular burner *f* and being upwardly open constitute a plurality of jet burners directed outside of and parallel with 30 the periphery of the heater body and for heating the outwardly projecting studs *a* in line therewith; and there are in addition to particularly represented by *g*^{*} a considerable number of further similar L-shaped tubular 35 members *g* making with those *g*^{*} a circular the several tubular L-shaped members par-series of upwardly directed gas burner jets, all taking their gas and air supply from the main burner *f* and for thoroughly heating 40 all of the outwardly extending radial studs of the heater body. A short L-shaped tubular member *j*² is connected with the main annular burner *f* at the inner side of the latter, and this member *j*² has connected at 45 its upstanding portion a circular burner *j* provided with upwardly open jet holes 15 directed into the circular vertical space within the heater body *A* and effective for the heating of the inner wall of such body

50 principally through the medium of the inwardly directed studs *a*² with which the body is internally provided. The heat from the flames or gas jet of the compound burner constituted by the main annular burner *f*, the 55 concentrically arranged secondary burner *j* and the outwardly and upwardly branching tubular burner members *g*, *g*^{*} is conserved by the provision of the thin metal sheath or shell *F* which is of somewhat larger diameter than the heater body *A*, having studs 60 comprised as substantially integral equipments thereof, said casing being open at both top and bottom,—its top, however, in the present instance being extended somewhat 65 above the top of the heater body *A* and

is provided with an internal flange *k* receiving supports on posts or studs *m*, *m* and retained by screws *m*²—such posts extending upwardly from the top of the heater body and being cast integrally therewith or otherwise provided thereto.

70 The entire heating apparatus has for the support thereof a constrictive metallic strap or band *G* preferably made in separable halves held together by clamping bolts *o*, *o*, 75 and comprising as a whole a band like portion 18 for engagement around the boiler tank *B* and a band like portion 19 for engagement around the upper peripheral portion of the heater body, which latter at its 80 top has a slight flange 20 which rests on the upper edge of the supporting band 19.

85 The chief advantage and value resulting from the present invention are obtained from the capability of the apparatus to heat any considerable quantity of water for domestic use in a surprisingly small time, it being appreciated that surfaces of the heater body are presented to be heated, and the same are heated directly at the base at the 90 periphery and at the inner wall by the action of gas flame not only in relation to the periphery and inner wall, but also in relation to the metallic stud provided at and transversely projecting from such walls; 95 and while an amplitude of gas may be burned for the required heating of the water, such gas burning need not be continued for any extended time, so that in the long run the heating apparatus is reasonably economical, as well as quick acting.

100 The transverse studs, in the apparatus as I have constructed it, are all integrally cast with the annular heater body, but I may construct the body, equipped with the studs 105 in the arrangement shown, and more or less numerous, as may be considered desirable by forming them separately and uniting or connecting them with the body in any of several manners known to be practicable. And 110 other minor changes may be made within the scope of my present invention without departing therefrom or sacrificing the substantial advantages thereof.

115 The tube or rod *t* axially located in the central space within the heater body prevents the jet flames from the central burner from merging one into another, but on the other hand insures that the heat therefrom will be distributed around about in relation 120 to the many internal studs *a*².

I claim:—

125 1. In a water heater, the combination with a hollow annulus closed both at the top and bottom, of a plurality of integral studs projecting from both the inner and outer walls of said annulus, a shell surrounding and spaced from said annulus, a water supply pipe entering the top of said annulus and terminating near the bottom thereof, a water 130

delivery pipe leading from the top of said annulus, and an annular burner comprising a body portion having a series of jets adapted to discharge against the lower face of said annulus, jets adapted to discharge within said annulus and against the studs of the inner face of said annulus, and a plurality of peripherally arranged, upwardly projecting jets which terminate above the lower edge of said shell and which discharge against the studs of the outer face of said annulus.

2. In an apparatus of the character described, an enclosed hollow, axially vertical, annular metallic body, a boiler tank, a water supply pipe leading from a lower portion of the boiler tank into said hollow annular body and a hot-water delivery pipe connected with the interior of said body, and a gas burner located below the hollow annular burner and having burner openings for flame impingements against the annular base, and also in relation to the internal and external portions, of the annular body.

25 3. A gas heater comprising an inclosed hollow axially vertical annular metallic body, provided with a series of metallic studs connected with, and extended transversely from, the wall of the said body, a water supply pipe and a hot water delivery pipe connected with the inclosed annular chamber in the body, and a gas burner below and for heating the body by burner flames directed against its base and against the said trans-

35 versely extended studs.

4. A heater comprising an inclosed hollow axially vertical annular metallic body, provided with metallic studs connected with and extended transversely from the walls of the body both inwardly and outwardly, a water supply pipe and a hot water delivery pipe connected with the inclosed annular chamber therein, and a gas burner below the hollow body comprising burner jets directed for gas flame impingements against the annular base of the body, against the inwardly extended studs in the space within the body and against the studs projecting outwardly from the body.

50 5. A gas heater comprising an inclosed hollow axially vertical annular metallic body, provided with a series of metallic studs connected with, and extended transversely from, the wall of the said body, a water supply

pipe and a hot water delivery pipe connected with the inclosed annular chamber in the body, a gas burner for directing flame against said base and against the said transversely extended studs, and a casing of larger diameter than, and inclosing the body, open at its top and bottom.

6. In a heating apparatus of the character described, an inclosed hollow, axially vertical, annular metallic body, having outwardly projecting lugs at its lower portion, a water supply pipe, and a hot water delivery pipe connected with the inclosed annular chamber therein, a gas burner below, and for heating, the annular body and supporting members for said burner connected with the latter and with said lugs.

7. In a heating apparatus of the character described, in combination, a gas heater comprising an inclosed hollow axially vertical annular metallic heater-body provided with a series of metallic studs connected with and extended transversely from the outer and inner surfaces of said body, and having at its base a plurality of outwardly projecting lugs, a water supply pipe, and a hot water delivery pipe, both connected with the inclosed annular chamber within the heater-body, a casing of larger diameter than, and inclosing, the heater-body, open at its top and bottom, and a compound gas burner comprising a main hollow annular burner-body having a gas supply pipe and provided with upwardly opening jets in its top directed against the annular base of the heater-body, and having L-shaped jets connected at intervals around its sides and upwardly directed parallel with the sides of the heater-body, certain of said jets having supporting engagements through the said lugs, for supporting the burner from the latter, and an L shaped tubular member connected with the inner side of the said main, annular burner, and having connected at its upstanding portion a hollow circular burner provided with upwardly open jet holes directed into the circular vertical space within the annular heater-body.
